US00D823837S

(12) **United States Design Patent** (10) **Patent No.:** **US D823,837 S**
(45) **Date of Patent:** **** Jul. 24, 2018**

(54) **POLARIZED ANTENNA**

(71) Applicants: **Aerohive Networks, Inc.**, Milpitas, CA (US); **Wistron Neweb Corporation**, Hsinchu (TW)

(72) Inventors: **Liangfu Zhang**, Hangzhou (CN); **George Gang Chen**, Fremont, CA (US); **Changming Liu**, Cupertino, CA (US); **Zhenye Cao**, Hangzhou (CN); **Shang-Sian You**, Hsinchu (TW); **Yu Tao**, Hsinchu (TW); **Chi-Kang Su**, Hsinchu (TW)

(73) Assignees: **Aerohive Networks, Inc.**, Milpitas, CA (US); **Wistron NeWeb Corporation**, Hsinchu (TW)

(**) Term: **15 Years**

(21) Appl. No.: **29/608,596**

(22) Filed: **Jun. 22, 2017**

Related U.S. Application Data

(62) Division of application No. 29/538,311, filed on Sep. 2, 2015.

CLAIM

We claim the ornamental design for the polarized antenna, as shown and described.

DESCRIPTION

FIG. 1 is a top and front perspective view thereof of the present invention;

FIG. 2 is a top view thereof;

FIG. 3 is a bottom view thereof;

FIG. 4 is a front view thereof; and,

FIG. 5 is a rear view thereof.

1 Claim, 3 Drawing Sheets
